UNITED STATES PATENT OFFICE.

JOSEPH H. SMITH, OF LYNN, MASSACHUSETTS, ASSIGNOR TO MARTHA ELIZABETH SMITH, OF LYNN, MASSACHUSETTS.

CORN AND BUNION SHIELD.

Application filed June 21, 1921. Serial No. 479,196.

To all whom it may concern:

Be it known that I, JOSEPH H. SMITH, a citizen of the United States, residing at Lynn, in the county of Essex and State of Massachusetts, have invented new and useful Improvements in Corn and Bunion Shields, of which the following is a specification.

This invention relates to shields of compressible material such as felt, adapted to be secured to a foot in position to protect a protuberance thereon such as a corn, or a bunion.

One object of the invention is to provide a shield having in its inner side an orifice adapted to receive a projecting protuberance, and a cover for said orifice which is adapted to conform to the height or projection of the protuberance and rest thereon without causing discomfort, the orifice and cover forming an adjustable socket, and the cover being displaceable to expose the protuberance and permit the application of salve thereto.

Another object is to provide improved means for anchoring a shield to the great toe of the wearer, in such manner as to adjustably confine the shield in its operative position.

The invention is embodied in the improvements which I will now proceed to describe and claim.

Of the accompanying drawings forming a part of this specification,—

Figure 1 is a side view of a bunion shield, without the anchoring means.

Figure 2 is a section on line 2—2 of Figure 1.

Figure 3 is a side view showing the anchoring means in an inoperative condition.

Figure 4 is a view similar to Figure 3, showing the anchoring means in condition for use.

Figure 5 is a view similar to Figure 4, showing the flap displaced.

Figure 6 is a side view of a corn shield.

Figure 7 is a section on line 7—7 of Figure 6.

The same reference characters indicate the same parts in all of the figures.

A shield embodying my invention is a normally flat flexible pad made of soft compressible material such as felt, and includes a base portion 12, having a protuberance-receiving orifice 13, the wall of which is con-

tinuous and preferably beveled, and a flap 14 connected at one end with the base portion and normally covering the orifice, the pad being also of soft compressible material such as felt, and forming a compressible cushion over a protuberance in the orifice. The flap is adapted to conform to the height of a protuberance such as a bunion, and to rest lightly on the same without causing discomfort. The orifice and flap collectively 60 form an adjustable closed socket, conforming to the height of the protuberance. The flap is displaceable, as shown by Figure 5, to expose the protuberance and permit the application of salve thereto, the salve being 65 confined in contact with the protuberance by the wall of the orifice and by the flap. The shield when used for bunions, is relatively 70 large, as shown by Figures 1, 2, 3, 4 and 5.

A corn shield embodying the invention, is 75 of smaller size, as shown by Figures 6 and 7. I prefer to make the shield from a single piece of felt having a slit 16, extending from one end partly to the opposite end, as shown by Figure 2, said slit partially subdividing the piece and forming the outer side of the base portion and the inner side of the flap. The orifice 13 is formed after the slit is cut and while the flap is displaced. The base and flap are, therefore, united by 80 an integral portion of the piece, so that there is no liability of the accidental detachment of the flap from the base.

The anchoring means of my invention used with a bunion shield, is embodied as 85 follows:

18 represents a flexible strap, preferably a piece of tape, attached at one end, as by stitches 20, to the outer side of the shield, and projecting therefrom at an angle as 95 shown by Figure 3. 21 and 22 represent short holding-down strips preferably of tape, united at their ends by stitches 20 to the outer side of the shield, the strips being free between their ends, so that the strap 18 may be inserted between them, and the outer side of the shield. The arrangement of the strips is such that the strap may be passed in one direction under the strip 21, across the outer side of the strip 22, and in the opposite direction under the latter, the strap being bent across one edge of the strip 22, as shown by Figure 4, so that the strap cannot reeve freely or accidentally under the strips. The strap is thus formed into a 110

loop, adapted to embrace a great toe and confine the shield in the desired relation to a bunion adjacent to the base of the toe. The size of the loop may be varied by withdrawing the strap from the strip 22, reeving it in one direction or the other under the strip 21, and again engaging it with the strip 22.

To facilitate the threading of the strap 10 under the strips 21 and 22, I stiffen the free end portion of the strap preferably by applying a coating 24 of shellac thereto.

The flap 14 may be made in a separate piece from the base portion 12, as shown by 15 Figures 6 and 7, and cemented to the base portion at 26 (Figure 7). A flexible reinforcing strip 27 of paper, muslin, or other suitable material, may be cemented, or otherwise secured to the hinged end portion of 20 the flap, and to the corresponding end portion of the body 12, said strip being adapted to be bent by the operation of displacing the flap. The strip 27 may be used on a shield in which the flap is integral with the body.

25 The protector, when embodied in a corn shield, may be secured in place by flexible strips, coated on one side with an adhesive, such as the well known Z. O. surgeons' plaster, the coated sides of the strips being 30 pressed against, and caused to adhere to the shield. The end portions of the strips project in opposite directions from the shield, and are adapted to be pressed against and caused to adhere to portions of a toe.

35 I claim:

1. A shield of the character stated, composed of a normally flat flexible pad of compressible material and comprising a base portion having an orifice, the wall of which 40 is compressible and formed to receive and entirely surround a protuberance, and a flap of similar material connected at one end with the base portion and normally covering the orifice, to constitute a compressible cushion over the protuberance, the flap being 45 adapted to conform to the projection of the

protuberance, and displaceable to expose the same, the orifice and flap forming an adjustable closed socket, adapted to receive and retain salve in contact with the protuber- 50

2. A shield of the character stated, composed of a single piece of compressible material, split from one end partly to the opposite end to form a base portion and an integral flap, the base portion being provided with an orifice normally covered by the flap, and adapted to receive a protuberance, the flap being adapted to conform to the projection of the protuberance, and displaceable 55 to expose the same, the orifice and flap forming an adjustable closed socket.

3. A bunion shield composed of a normally flat flexible pad of compressible material having a bunion-receiving orifice in its inner side, formed to receive and entirely surround a protuberance, and a flap of similar material, connected at one end with the base portion and normally covering the orifice, one end portion of the outer side of the 65 shield being provided with adjustable anchoring means comprising a flexible strap attached at one end to the shield, and a pair of holding-down strips attached to the shield and arranged to confine two portions 70 of the strap against the outer side of the shield, the strap being movable endwise under said strips, and the arrangement being such that the strip may be bent across one edge of one of the strips, to prevent 75 reeving of the strap.

4. A bunion shield substantially as specified by claim 3, the free end of the strap being stiffened to facilitate its insertion under said strips.

85 5. A shield substantially as specified by claim 1, provided with a reinforcing strip secured to the flap and to one end of the base portion.

In testimony whereof I have affixed my 90 signature.

JOSEPH H. SMITH.
